TIRE

Charles A. San Giovanni, Huntington Station, N.Y., assignor to The B. F. Goodrich Company, New York, N.Y., a corporation of New York

Filed Dec. 11, 1969, Ser. No. 20,454

Term of patent 14 years

Int. Cl. D12—14
U.S. Cl. D90—20

The figure is a perspective view of a tire showing the new design, it being understood that the opposite side of the tire is the same as the side shown.

The characteristic features of the design reside in the sidewall configuration, the outline of the entire tire being shown to illustrate the location therein of the novel portion.

I claim:

The ornamental design for a tire, substantially as shown and described.
